TAG-FASTENER AND GUIDE THEREFOR

Samuel Weiss, Brooklyn, N. Y.

Application December 12, 1934, Serial No. 757,081

7 Claims. (Cl. 40—24)

My invention relates to improvements in tag fasteners and guides therefor and it consists in the novel features which are hereinafter more fully described.

5 One of the objects of my invention is: to produce a perfected tag fastener, and to provide the prongs of the fastener with a means for preventing or limiting the deflection of the prongs with relation to each other in a direction trans-

10 versely to the plane of the fastener.

Another object of my invention is: to limit the relative deflection of the prongs of the fastener from each other in the plane of the fastener in a direction to open the fastener.

15 A further object of my invention is: to limit the relative deflection of the prongs of the fastener in a direction to close the fastener.

A still other object of my invention is: to provide my tag fastener with a means for locking 20 the prongs thereof in position after attaching the same to a garment.

Another object of my invention is: to have the said fastener with the said limiting means and locking means effective, simple, durable and 25 inexpensive.

Other objects and advantages will hereinafter appear.

I attain these objects by the tag fastener and guide therefor several forms of which are illustrated in the accompanying drawing; or by any 30 mechanical equivalent or obvious modification of the same.

In the drawing Fig. 1 is a side elevation of one form of my tag fastener and guide therefor; Fig. 2 is a sectional plan of the same on the line 35 2—2 of Fig. 1; and Fig. 3 is a top plan view of the same.

Fig. 4 is a side elevation of another form of my tag fastener and guide therefor, including 40 also a locking means, which is hereinafter described; and Fig. 5 is a sectional plan of the same on the line 5—5 of Fig. 4.

Fig. 6 is a side elevation of a still other form of my tag fastener and guide therefor; and Fig. 45 7 is a side elevation of a modification of the form of my tag fastener and guide therefor which is shown in Figs. 1, 2 and 3.

Similar numerals refer to like parts throughout the several views.

50 11 designates one of the prongs in the form of my tag fastener, which is shown in Figs. 1, 2 and 3, and 12 designates the other prong.

The prongs 11 and 12 are preferably initially stressed and have thereon inclined branches 55 13 and 14 respectively, which cross each other and

terminate in engaging members 15 and 16 respectively, which are disposed to grip with their pointed ends a portion of a garment placed therebetween.

By pressing the prongs 11 and 12 towards each other the members 15 and 16 are separated from each other; on releasing the prongs 11 and 12, the latter resume their position as shown in Fig. 1 of the drawing, thereby causing the members 15 and 16 to move towards each other and the ends thereof to grip a part of a garment or fabric which may be placed therebetween. 5

To prevent the prongs 11 and 12 with the inclined branches 13 and 14 thereon from being unduly deflected with relation to each other in a direction transversely to the plane of the fastener, I provide a control member in the shape of a guide ring or collar 17, which slidably encircles the branches 13 and 14 at the point of their crossing each other for all positions of the 10 branches 13 and 14. 15

When the prongs 11 and 12 are pressed towards each other the guide or collar 17 is thereby lowered in position; on releasing the prongs 11 and 12, the guide or collar 17 is raised by the branches 20 13 and 14 as the latter return to their original position. 25

The guide ring or collar 17 fits snugly on the branches 13 and 14 and keeps them from separating from each other in a direction transversely to the plane of the fastener, without interfering with their movement in the plane of the fastener. 30

In the form of my tag fastener and guide therefor which is shown in Figs. 4 and 5, the prongs 21 and 22 are initially stressed and have thereon inclined branches 23 and 24 respectively which cross each other and terminate in engaging members 25 and 26. The branches 23 and 24 have thereon lower longitudinally disposed offsets 27 and 28 respectively and upper longitudinally disposed offsets 29 and 30 respectively. 35

A guide ring or collar 17a girds the branches 23 and 24 at the point of their crossing each other and acts similarly to the guide ring or collar 17 in the modification shown in Figs. 1, 2 and 3. 40

A control member in the shape of a locking collar 31, which is larger than the guide ring 17a, is shown in Fig. 4 as encompassing the offsets 27 and 28 after it has been transferred to this position from its alternative position which is shown in dotted lines at 31a, where the collar 31 has been encompassing the offsets 29 and 30 respectively. 45

It is evident from the drawing that in the position at 31a the locking collar will permit the engaging members 25 and 26 to be separated or 50 55

5 moved in a direction away from each other by pressing the prongs 21 and 22 in the plane of the fastener towards each other; but it will limit the motion of the said engaging members towards each other.

10 In the position shown at 31 the locking collar will prevent the separation of the engaging members 25 and 26 as is evident from the drawing.

15 When a portion of a garment or fabric is engaged by the members 25 and 26 the collar 31 is moved by hand from the position at 31a to that at 31, passing over the guide ring 17a, thereby locking the fastener on to the engaged garment.

20 The resilience of the metal parts of the fastener causes the offsets 29 and 30 to press on the interior of the locking collar 31, thereby producing a frictional resistance to the removal of the said locking collar therefrom.

25 When it is desired to disengage the fastener from a garment the said locking collar 31 is removed by hand from the offsets 29 and 30 against the said frictional resistance.

30 The guide ring 17a may be omitted, if desired; the locking collar 31 may then be made considerably narrower than as shown in Fig. 5 of the drawing; and it will also act to prevent the separation of the engaging members in a plane which is transverse to the plane of the fastener.

35 In the form of my tag fastener and guide therefor, which is shown in Fig. 6, 41 and 42 are the prongs of the fastener which are initially stressed and have thereon inclined branches 43 and 44 respectively which terminate in engaging members 45 and 46 respectively.

40 The branches 43 and 44 have thereon lower lateral offsets 47 and 48 and upper lateral offsets 49 and 50.

45 A guide ring or collar 17b girds the branches 43 and 44 at the point of their crossing each other and acts in part as in the modification shown in Figs. 1, 2 and 3.

50 It is evident from the drawing that the guide ring 17b also acts in association with the said lateral offsets 47 and 48 to limit the relative deflection of the prongs 41 and 42 in the plane of the fastener in a direction to open the fastener; the guide ring 17b likewise acts in association with the lateral offsets 49 and 50 to limit the relative deflection of the prongs 41 and 42 in the plane of the fastener in a direction to close the fastener, thereby preventing the engaging members 43 and 44 from sliding too far past each other at their ends.

55 One of the offsets 47 or 48 may be omitted in cheaper fasteners; likewise one of the offsets 49 or 50 may be omitted in less perfect fasteners, if desired.

60 In the form of my tag fastener and guide therefor, which is shown in Fig. 7, the prongs 51 and 52 are initially stressed and have thereon inclined branches 53 and 54, respectively, which terminate in engaging members 55 and 56 respectively.

65 A guide ring or collar 17c is positioned in a plane which is longitudinally disposed with relation to the fastener and encircles the branches 53 and 54 at the point of their crossing each other, thereby limiting the deflection of the prongs 41 and 42 in a direction transversely to the plane of the fastener.

70 It is evident from Figs. 1 and 7 of the drawing that by varying the initial angles at which the branches 13 and 14 in Fig. 1, or the branches 53 and 54 in Fig. 7, cross each other, the range of sliding of the member 17 or 17c on said branches

75 will also be varied; it is also evident that with a given initial angle for said branches, the range of sliding of said member on said branches will be varied with the variation of the shape and size of the said member.

80 It is, therefore, evident that, by assigning a suitable initial angle of intersection to said branches and a suitable size and shape to the said member, the range of sliding of said member on said branches may thereby be predetermined, thereby also predetermined the limit of variation of the deflection of the prongs 11 and 12 in Fig. 1, or of the prongs 51 and 52 in Fig. 7, in a direction substantially parallel to the plane of the fastener.

85 Variations are possible, and part of my invention may be used without other parts.

90 I do not, therefore, restrict myself to the details as shown in the drawing; but I intend to include also all mechanical equivalents and obvious modifications of the same within the scope of my invention.

95 I claim as my invention and desire to secure by Letters Patent:

1. A tag fastener having a pair of initially stressed prongs, suitably inclined branches on said prongs disposed to cross each other at a variable point through a desired range of variation of the latter, said branches terminating in pointed engaging members which are disposed to grip with their pointed ends a portion of a garment placed therebetween, and a control member of suitable shape and size automatically slidably encompassing the said branches at said point, whereby, in cooperation with parts on said branches disposed to intercept said control member, to limit the said range of variation, thereby also limiting to a desired extent the range of deflection of said prongs in a direction substantially parallel to the plane of said fastener.

100 2. A tag fastener having a pair of prongs, inclined branches on said prongs, crossing each other at a variable point and terminating in pointed engaging members, disposed to grip with their pointed ends a part of a garment therebetween, a control member automatically slidably encompassing the said branches and a means on said prongs for duly restricting the range of sliding of said control member, whereby to limit the deflection of said prongs in a direction substantially parallel to the plane of the fastener.

105 3. A tag fastener having a pair of prongs, inclined branches on said prongs, crossing each other at a variable point and terminating in pointed engaging members, disposed to grip with their pointed ends a part of a garment therebetween, a guide member automatically slidably encompassing the said branches at said point, whereby to limit the deflection of said prongs in a direction transversely to the plane of the fastener and a means on said prongs for duly restricting the range of sliding of said control member, thereby limiting the deflection of the prongs in a direction substantially parallel to the plane of the fastener.

110 4. A tag fastener having a pair of prongs, inclined branches on said prongs, crossing each other at a variable point and terminating in pointed engaging members, disposed to grip with their pointed ends a part of a garment therebetween, a control member, automatically slidably encompassing the said branches, and stop means on said prongs for restricting the range of sliding of said control member, whereby to limit the deflection of said prongs in a direction substantially parallel to the plane of the fastener.

5. The elements of claim 4, said stop means comprising one or more suitably disposed offsets on said prongs for intercepting said control member, whereby to limit the range of sliding thereof.
- 5 6. A tag fastener having a pair of prongs, inclined branches on said prongs, crossing each other at a variable point and terminating in engaging members, disposed to grip a part of a garment therebetween, a guide member, slidably encompassing said branches at said point, thereby limiting the deflection of said prongs in a direction transversely to the plane of the fastener, combined with one or more lateral offsets on said branches, located on the side of said point which 10 is near said engaging members, thereby limiting the deflection of said prongs in the plane of the fastener in a direction to close the fastener.
- 10
- 15
7. A tag fastener having a pair of prongs, inclined branches on said prongs, crossing each other at a variable point and terminating in engaging members, disposed to grip a part of a garment therebetween, a guide member, slidably encompassing said branches at said point, thereby limiting the deflection of said prongs in a direction transversely to the plane of the fastener, combined with one or more lateral offsets on said branches, located on the side of said point which 10 is near said engaging members, thereby limiting the deflection of said prongs in the plane of the fastener in a direction to close the fastener.
